C. Harris and P. W. Joiner of Cincinnati Ohio
Letters Patent No. 2338 dated June 12, 1866.

Design for a Parlor Stove

The Schedule referred to in these Letters Patent and making part of the same

To all whom it may concern

Be it known that we compound
Harris and Paul W. Joiner, both of Cincinnati, County of Hamilton State of Ohio, have invented a new and improved design for Coal and Wood Parlor Stoves, to be known and called the "Parlor Belle" and we do hereby declare that the following is a full and exact description thereof reference being had to the accompanying photographs and to letters of reference marked stereonumeral A showing a perspective view of the stove.

That we claim as our invention and desire to secure by letters patent is the design for Coal and Wood Parlor Stoves, as shown and described.
